STOOL ATTACHMENT FOR BARBERS' CHAIRS

Charles E. Paden, Pittsburgh, Pa.

Application February 8, 1946, Serial No. 646,303

5 Claims. (Cl. 155—81)

1

This invention relates to improvements in stool attachments for barbers' chairs by means of which the barber may be seated while rendering tonsorial service to the occupant of the barber's chair.

An object of the invention is to provide a device which may be attached to any standard form of barber's chair.

Another object of the invention is to provide a device which is capable of being adjusted to accommodate operators of various sizes.

A further object of the invention is to provide a device that is simple in construction, efficient and reliable in use and may be easily installed.

With the above and other objects and advantages in view the invention consists of the novel details of construction, arrangement and combination of parts more fully hereinafter described, claimed and illustrated in the accompanying drawings in which:

Figure 1 is a side elevation of a barber chair with an embodiment of the invention attached thereto.

Figure 2 is a rear view looking in the directions of the arrows on the line 2—2 of Figure 1.

Figure 3 is a sectional view on the line 3—3 of Figure 1.

Figure 4 is a sectional view on the line 4—4 of Figure 3.

Figure 5 is a sectional view on the line 5—5 of Figure 1 and

Figure 6 is a top plan view of Figure 1 showing the various portions in which the attachment may be moved.

Referring more in detail to the drawings the reference numeral 10 designates a conventional barber's chair having the pedestal 12 enlarged base 14 the vertically adjustable standard 16 on the upper end of which is positioned the seat 18 of the barber's chair having the usual adjustable back 20 hinged to the seat 18 arm rests 22 and the members 24 carrying the foot rests 26 and 28 respectively.

The attachment embodying the present invention comprises the semi-circular channel sections 30 and 32 respectively in which rollers 34 are rotatably mounted by means of vertically disposed bolts 36. The ends of the sections 30 and 32 are bent outwardly as shown in Figure 3 at 37 to receive the bolts 38 on which are mounted springs 40. Thus the sections can be adjusted to fit pedestals of various sizes and by tightening of the nuts 42 on bolts 38 the sections can be maintained in close yet movable contact with the pedestal through the medium of the rollers 34.

2

Caps or housings 44 are positioned over the meeting ends of the sections and when the bolts 46 are tightened, the top and bottom projecting sides of the box overlying the sections are compressed to grip the outer surfaces of the sections, so that the housings are retained in place by the bolts 46. This protects the user of the chair from coming in contact with the ends of the bolts 38.

At the center of the sections between their ends and in opposed relation to each other sockets 48 are provided to receive the parallel aligned arms 50 of the chassis 52 and set screws 54 in the sockets 48 retain the arms in fixed relation to the sockets.

15 The arms 50 are received at their opposite ends in the Y couplings 56 having the legs 58 connected thereto and extending at a forty-five degree angle therefrom on which are mounted the caster wheels 60 which contact the periphery of the base 14. Extending rearwardly from the couplings 56 in parallel relation with each other are the members 62 which are connected at their opposite ends to elbows 64 which are connected to a T-coupling 66 by means of short members 68.

20 Extending downwardly from the coupling 66 is a leg 70 having a caster wheel 72 on the lower end thereof and a brace rod 74 connects the coupling 66 of the caster wheel 72 to the member 18 binding the coupling 66 of the caster wheels 60. Extending downwardly from the coupling 66 is a leg 70 having a caster wheel 72 on the lower end thereof and a brace rod 74 connects the coupling 66 of the caster wheel 72 to the member 18 binding the coupling 66 of the caster wheels 60.

25 30 If desired two caster wheels can be used to replace caster wheel 72 and the assembly would be similar to the arrangement for the caster wheels 60. Adjacent the sockets 48 the arms 50 are provided with rubber foot rests 82.

35 A stool 84 having the adjustable seat 86 is mounted on a platform 88 which by means of members 90 is mounted on the arm 50 and members 62 and the members 90 are provided with transverse bolt shafts 92 to support rollers 94 40 in contact with the upper and lower surfaces of the arms 50 and members 62 thus the platform can be moved away from or toward the barber's chair as desired by the occupant of the stool 84. The platform is provided with the depending marginal flange 96 and the stool 84 is secured to the upper surface of the platform 88 by bolt 98 and the members 90 are secured to the undersurface of the platform 88 by bolt 100.

45 When the operator is at work he may move 50 the chassis 52 around the chair 10 as he desires while seated or he may move it out of his way while standing. The caster wheels 60 being in contact with the base at all times the chassis will remain at a fixed relation thereto but by 55 means of the movable platform 88, the operator

may move himself toward or away from the occupant of the chair 10 and he can either place his feet on the rests 82 or he can place his feet on the platform as he desires.

It is believed that the operation and advantages of the attachment will be apparent to those skilled in the art and it is to be understood that changes in the details of construction, arrangement and combination of parts may be resorted to provided they fall within the spirit of the invention and the scope of the appended claims.

Having thus described the invention what is claimed as new and desired to be secured by Letters Patent is:

1. A device of the character described for use with a barber's chair comprising an annulus surrounding the pedestal base of the chair, rollers mounted in said annulus, sockets on said annulus receiving arms of a chassis, movable with relation to said chair by means of caster wheels, a platform movably mounted on said chassis and a stool supported by said platform.

2. The invention as in claim 1 wherein said annulus is sectional, means is provided for adjustably connecting the sections to each other and means is provided for housing said connecting means.

3. The invention as in claim 1 wherein said chassis comprises parallel arm Y-couplings connected to said parallel arms, legs connected to 30

said couplings, caster wheels on said legs contacting the base of the chair at an angle of forty-five degrees, parallel members connected to said couplings and connected to a leg, having a caster wheel rearwardly of but intermediately of said first mentioned caster wheels.

5. The invention as in claim 1 wherein said platform is provided with parallel members having means therein for supporting rollers in contact with the arms of the chassis for movable relation therewith.

10 6. The invention as in claim 1 wherein means is provided for securing said stool to said platform and said stool is provided with an adjustable seat.

15 CHARLES E. PADEN.
